UNITED STATES PATENT OFFICE.

GEORGE MATTA, OF BRADDOCK, PENNSYLVANIA.

FLYING MACHINE.

1,408,115.

Specification of Letters Patent. Patented Feb. 28, 1922.

Application filed March 18, 1920. Serial No. 366,902.

To all whom it may concern:

Be it known that I, GEORGE MATTA, a resident of Braddock, in the county of Allegheny and State of Pennsylvania, have 5 invented a new and useful Improvement in Flying Machines, of which the following is a specification.

This invention relates to flying machines.

More particularly it relates to such machines so constructed and driven as not to require any vanes, all of the supporting means being in the form of driven propellers. Another principal object of the invention is to secure a constantly resistant 10 contact between revolving propellers and the air in which they revolve. Another object is to connect to propeller blades a supplementary driving mechanism adapted to move them up and down out of their normal 15 plane of revolution with a flapping motion, in order to break up the helix of air which tends to form in the plane of rotation of the propeller. Another object is to so mount the propeller blades that their angle of contact with the air may change when the free 20 ends of the blades are moved up and down. Another object is to so mount two or more propellers that the air currents formed thereby blow against each other.

30 Referring to the drawings, Fig. 1 is a diagrammatic side elevation of my machine, showing the arrangement of propellers and supplementary driving devices; Fig. 2 is a diagrammatic plan view; Fig. 3 is a vertical sectional view and Fig. 4 is a diagram showing the change of angularity of the propeller blades as they are pulled up and down.

The present aeroplanes are supported by 40 broad planes, similar to the wings of sailing bird, and their upward travel is secured by a motor driven propeller, usually situated in front of the body of the machine, and ahead of the supporting planes, which pulls in 45 opposition to the planes.

It is a well known principle of aeronautics that when a body is pulled through the air in opposition to an angularly disposed upwardly inclined resisting element, the body 50 tends to rise in the air. This is clearly illustrated by the ordinary kite, which when pulled forward against the wind, readily rises in the air, carrying a considerable weight if necessary.

55 I propose to utilize somewhat the same principle in connection with the present in-

vention, but to substitute for the planes two propellers blowing against each other. To this end I provide a driven propeller A, at the rear of the body B of my machine, and 60 at the forward end of the body I provide a normally horizontal shaft carrying a propeller C, and blowing against the rear one, the two acting in opposite directions, and their air backlashes being opposed to each 65 other.

Both the forward and rear propellers are mounted so that their shafts may be varied in angularity, to provide for different driving conditions. In order that the angularity 70 of these shafts may be regulated, levers 1 and 2 and flexible connections 3 and 4 are provided, respectively connected to the propellers A and C, in the manner illustrated in Fig. 1. Similar lines and connections 75 may be provided to regulate lateral angularity.

As will be seen in Fig. 3, the driving shaft of the forward propeller C is connected to a transverse shaft that is mounted with one 80 end higher than the other. Consequently, when the propeller shaft is raised it is also directed slightly to one side. This will give a rotative movement to the whole machine when it is rising straight up from the 85 ground.

It is a well known principle of aeronautics that the ordinary form of propeller, having its blades following each other in the same general plane, tends to form a helix or 90 pocket of air around the propeller, when it is driven very fast. This is much the same as when a paddle is used to stir a liquid in a circular container. After a few turns the liquid goes round and round with the 95 paddle rather than the paddle going through the liquid.

One of the objects of the present invention is to break up such a helix. This is done by connecting to each blade of my propeller, at some distance from the inner ends thereof, a spring 5, connected to a connecting rod 6, which is driven as more fully described below. The spring is mounted between and around the ends of connecting 100 rod 6, as drawn, so as to give a limited extension. The inner ends of the propeller blades are mounted so as to leave them free to change in angularity and to move up and down, in and out of the normal plane of 105 revolution. The connecting rod 6 is connected to a blade of the propeller at one end and

at the other to a crank arm 7, mounted on driven shaft 8. The shaft 8 is driven by any desired means such as pinions on its ends meshing with a driving gear mounted 5 in any convenient manner as indicated in Fig. 2, and has a clutch connection to the motor, so that it may be driven or not at the will of the operator. Such gearings are not a part of this invention and therefore are 10 not described herein.

When the crank arrangement just referred to is operating, the propeller blades are waved, that is, driven up and down out of the plane of normal revolution, and thus 15 strike and break up the circular currents of air which would otherwise be formed in the path of their revolution.

The springs 5 are attached to the rear edge 20 of the blades 7. These springs are adapted to normally hold the blade at a predetermined angle correct for driving. But when the blade is pulled sharply down by the crank, the extra resistance turns the following edge of the blade up, so the angularity 25 changes, as shown in Fig. 4. This breaks up the air helix.

The spring permits the turning back of the following edge of the blade to a limited extent only, as above stated.

30 It will be understood that I may use two or four blades to each propeller. Where only small blades are used it is not necessary to apply the flapping arrangement. I may use one, two, or more propellers, and may use 35 my flapping arrangement with only one propeller, in order to increase the resistance of the air about the driving blades.

When either of the propellers A or C is turned slightly to one side or the other from 40 the axis of the body, the whole machine will thereby be given a slowly rotating movement and will go round as it goes up. This is advantageous when the machine is being raised without forward travel.

45 I have not attempted to describe fully any gearing, or steering apparatus, since such mechanism is already standardized and well known, and may be applied to this apparatus in the ordinary and usual manner.

I provide suitable clutches and control 50 apparatus for connecting and disconnecting the flapping arrangement above described, and it will be understood that I use this arrangement or not, according to the conditions under which the machine is operated. 55 These details of mechanism are not a part of this invention and are not shown.

Many advantages and uses of this invention above set forth will be apparent to those familiar with such machines. I do not desire 60 to be limited to the particular apparatus set forth, which may be varied in a number of ways to secure the same results, without departing from the broad principles of my invention. 65

I claim:

1. In a flying machine, a propeller in front adapted to pull the machine forward, a propeller behind adapted to pull the machine backward and upward, the currents of 70 air from the two propellers blowing against each other, and means to direct the forward propeller laterally so as to cause the machine to go round as it goes up.

2. In a flying machine a propeller blade 75 pivotally mounted to its driving shaft, a crank arrangement adapted to pull the propeller blade up and down out of its normal plane of revolution, and a resilient connection to the rear edge of the propeller blade 80 to permit its angularity to vary as it is pulled out of the said normal plane of revolution.

3. A flying machine comprising a forwardly directed propeller, a rearwardly directed propeller, means to drive the forward propeller to advance the machine, means to drive the rear propeller to retard the machine, means to independently change the vertical angularity of each of the propellers, 90 and means to change the plane of revolution of the individual blades of each of the propellers.

In testimony whereof, I have hereunto set my hand.

GEORGE MATTA.

Witness:

G. G. TRIEL.
